UNITED STATES PATENT OFFICE.

WALTER BRUCE WILLS, OF BALTIMORE, MARYLAND.

STRAINER.

Application filed April 20, 1921. Serial No. 462,871.

To all whom it may concern:

Be it known that I, WALTER BRUCE WILLS, a citizen of the United States, residing at Baltimore city, State of Maryland, 5 have invented certain new and useful Improvements in Strainers, of which the following is a specification.

This invention relates to culinary and similar strainers which are carried by an 10 extensible supporting frame, and its object is to provide an improved connection between the strainer and its supporting frame, as will be pointed out in the detailed description appearing hereinafter.

15 In order that the invention may be better understood, reference is had to the accompanying drawing forming a part of this specification, and in said drawing—

Figure 1 is a side elevation of the 20 strainer; Fig. 2 is an end view with the supporting frame in section; Fig. 3 is a plan view; Fig. 4 is a detail in perspective showing the means for connecting the strainer to its supporting frame; Fig. 5 is 25 a plan view showing a modified form of the means employed for connecting the strainer to its supporting frame; Fig. 6 is a detail in perspective showing a fragment of the modified structure, and Fig. 7 is a 30 detail perspective view of a further modification.

Referring specifically to the drawing, 10 denotes an ordinary bowl-shaped strainer having its edge reinforced by a sheet metal 35 ring or band 11. The supporting frame of the strainer is made of wire, and it is composed of two slidably connected members so that it may be lengthened or shortened. Each frame member is composed of side 40 bars 12 and cross bars 13 connecting the outer ends thereof. The side bars of each frame member have eyes 14 at their inner ends through which slidably pass the side bars of the other frame member. This is 45 a well known construction, and hence further description thereof is not necessary.

The strainer 10 is mounted between the side bars 12 of the supporting frame, and the present invention relates more particularly to the connection between these parts, and which will now be described.

The marginal band 11 of the strainer 10 is encircled externally by a wire ring 15 having at diametrically opposite points a 55 connection with the frame side bars 12. This connection is produced by making out-

ward bends in the ring 15 to form two outwardly extending arms 16 and a cross bar 17 connecting the latter at their outer ends. A hook is then secured to the cross 60 bar 17 close to its junction with the arms 16. This hook is made of wire which is bent to form a cross bar 18 and downwardly projecting arms 19 at the ends of the latter, said arms having their outer ends bent 65 inwardly, as shown at 20, the cross bar 18 being rigidly connected to the cross bar 17, by being spot-welded thereto. The parts 20 constitute the bill of the hook, whereas the parts 19 are the shank of the hook, 70 Each hook is constructed in the manner described. The hooks are downturned and inwardly presented to come beneath the side bars 12, the length of the part 20 from the bends 16 being sufficient to accommodate the 75 side bars. The length of the parts 20 is such that the ends thereof lie close to the side of the band 11, whereby separation of the hooks and the side bars 12 of the supporting frame is effectually prevented. The 80 top of the band 11 is beaded, as shown at 21, and the ring 15 seats beneath said bead, which prevents the strainer 10 from slipping downwardly out of the ring.

The structure whereby the strainer 10 is 85 connected to the side bars 12 of its supporting frame is very simple and efficient, and it can also be easily and cheaply produced and assembled.

The ring 15 is made of a single piece of 90 wire, but it can also be made in two pieces as shown in Fig. 5. The two sections of the wire constituting the ring are denoted by the reference characters 22 in Fig. 5. Each section of the ring has an outward bend 23 95 at its ends, and when the sections are assembled, the ring has two laterally spaced outward bends at diametrically opposite points. Each hook in this structure is composed of a cross bar 24 having downturned bends 25 100 at its ends which terminate in lateral bends 26. The hooks are attached to the ring by placing the cross bars 24 over the outer ends of the respective pairs of bends 23, and spot-welding the same thereto. This structure 105 also produces downturned and inwardly directed hooks at diametrically opposite points on the ring, said hooks engaging the side bars 12 in the same manner as the hooks first described. The parts 24 provide the 110 connections between the two ring sections 22. The structure shown in Fig. 7, constitutes

a cross bar 28, and laterally projecting arms 29, at the ends of the bar 28, said arms have 30, and rigidly connected to the cross bar 17, 5 by being spot-welded thereto.

I claim:

1. The combination with a strainer and a supporting frame having side bars between which the strainer seats; of a ring encircling 10 the strainer and having pairs of integral outward bends at diametrically opposite points, cross bars connecting the outer ends of said bends, and downturned and inwardly directed hooks secured to the cross bars, in 15 which hooks the side bars of the supporting frame seat.
2. The combination with a strainer and a supporting frame having side bars between which the strainer seats; of a ring encircling 20 the strainer and having pairs of integral outward bends at diametrically opposite points, cross bars connecting the outer ends of said bends, and hooks in which the side

bars of the supporting frame seat, said hooks being separate from the ring and composed 25 of shanks which are connected to the outer ends of the aforesaid cross bars to extend downwardly therefrom, and have inturned lower extremities to seat beneath the side bars of the supporting frame.

3. The combination with a strainer and a supporting frame having side bars between which the strainer seats; of a ring encircling 30 the strainer and having pairs of integral outward bends at diametrically opposite 35 points, cross bars connecting the outer ends of said bends, and hooks in which the side bars of the supporting frame seat, said hooks being separate from the ring and composed of cross bars having shanks provided on the 40 ends thereof, said shanks being downwardly and inwardly directed to seat beneath the side bars of the supporting frame.

In testimony whereof I affix my signature.

WALTER BRUCE WILLS
